UNITED STATES PATENT OFFICE

156,646

PAPER DISPENSER

William E. Mell, Chicago, Ill., assignor to Mell-Hoffmann Mfg. Co., Chicago, Ill., a corporation of Delaware

Application June 22, 1948, Serial No. 147,132

Term of patent 3½ years

(Cl. D4—3)

To all whom it may concern:

Be it known that I, William E. Mell, a citizen of the United States, residing at Chicago, Cook County, Illinois, have invented a new, original, and ornamental Design for a Paper Dispenser, of which the following is a specification, reference being had to the accompanying drawing, forming a part thereof.

Fig. 1 is a perspective view of the paper dispenser; and

Fig. 2 is a perspective view of the same with the covers partially opened.

I claim:
The ornamental design for a paper dispenser, substantially as shown.

WILLIAM E. MELL.
